A. B. DISS.

TOP BEARING DETACHABLE CASTER.
APPLICATION FILED MAR. 10, 1916.

1,202,274.

Patented Oct. 24, 1916.

UNITED STATES PATENT OFFICE.

ALBERT B. DISS, OF NEWARK, NEW JERSEY.

TOP-BEARING DETACHABLE CASTER.

1,202,274.

Specification of Letters Patent. Patented Oct. 24, 1916.

Application filed March 10, 1916. Serial No. 83,222.

To all whom it may concern:

Be it known that I, ALBERT B. DISS, a citizen of the United States, residing at Newark, in the county of Essex and State of New Jersey, have invented certain new and useful Improvements in Top-Bearing Detachable Casters, of which the following is a specification.

My invention relates to furniture casters 10 of the type in which the weight to be supported is borne by the top of the pintle which frictionally engages a bearing surface formed at the top of the sleeve through which the pintle extends.

My invention relates particularly to improvements in such constructions, whereby various advantages are secured, including an improved top bearing for the pintle, means whereby the caster may be detachably secured to the furniture leg to be supported, and to the provision of a leg mount or supporting plate so formed as to provide a sliding shoe for the furniture leg when the caster wheel and pintle are not in place.

In my preferred constructions, the leg-supporting plate comprises a disk having either an upturned peripheral flange, adapted to fit about and protect the bottom of a tubular leg, or having upturned projections 30 adapted to fit within the bottom of the leg. A sleeve extends upwardly from the central opening of the leg-supporting plate, and is closed at the top to form a top pintle bearing. A spring frame is used, having a

transverse portion secured across the top of the sleeve, and having depending arms adapted to resiliently engage within the leg. These arms may extend within the marginal flange or upturned projections of the disk,

when the device is not positioned in a leg, to prevent them from being bent too far outwardly. The sleeve which I prefer to use is so formed as to have two portions extending across the top, one lying upon and crossing the other at an angle, which can be accomplished by making the sleeve of a pair of metal strips bent to inverted U-shape and placed at right angles to each other, with the top portion of one strip overlying the other.

The double thickness of metal thus formed at the top of the sleeve enables me readily to spot-weld or rivet the spring frame to the same, this resulting in an exceedingly rigid top bearing and an inexpensive but effective construction. The pintle carrying the journaled caster wheel is adapted to extend up-

wardly through the sleeve into contact with the bearing formed at the top of the sleeve. The leg-support is usually provided on its lower side with a downwardly curved surface or surfaces adapted to slidingly support the construction when the same is mounted on the bottom of a leg, but the pintle and caster wheel are not in place.

As a modification of the structure first referred to, the flange or upturned projections of the leg-supporting disk may be omitted, in which case the spring frame will have a somewhat different construction.

In order that a clearer understanding of my invention may be had, attention is hereby directed to the accompanying drawings forming part of this application and illustrating certain embodiments of my invention.

In the drawings, Figure 1 represents a side elevation of my improved caster applied to a tubular leg shown in section, Fig. 2 is a front elevation of the same, the leg not being shown, Fig. 3 is a vertical section on line 3-3 of Fig. 2, the leg, however, being shown, Fig. 4 is a view similar to Fig. 1, showing the construction when the pintle and caster wheel are detached, Fig. 5 is a vertical section, similar to Fig. 3, of a modified construction, the sleeve being shown in side elevation, Fig. 6 is a horizontal section taken on line 6-6 of Fig. 5, and Fig. 7 is a view similar to Fig. 3, showing a further modified construction.

Referring to the drawings, the leg-supporting plate or disk 1 may be provided with an upturned peripheral flange 2 (see Figs. 1 to 4), within which the tubular leg 3 to be supported is mounted, the lower end of the leg fitting slidingly within flange 2. The sleeve 4 extends upwardly from the central opening in disk 1, the spring frame 5 being secured to sleeve 4 at the upper end of the latter. The pintle 6 extends upwardly through the central opening in disk 1 and through the sleeve 4 into contact with the metal extending across the top of the sleeve. The caster wheel 7 is journaled within the horn 8, to the upper transverse portion 9 on which the pintle is secured in the usual manner.

The sleeve 4, as stated, is preferably formed of a pair of metal strips 10 and 11 arranged at right angles to each other with the transverse top portion 10' of strip 10 crossing and lying upon the transverse top

portion 11' of strip 11. The depending portions of the strips are bent into tubular form, preferably with their adjacent edges abutting. The sleeve is rigidly secured to the leg-supporting disk 1 by crimping the lower ends of the strips forming the sleeve around the edges of the central opening in leg-supporting plate 1, the strips 10 and 11 thus being formed with peripheral flanges 12 and 13 above and below disk 1, and resting in contact with the metal of the disk 1 surrounding the opening therein. The strips of the sleeve are preferably provided with pressed-in portions 14, to form inwardly projecting ridges or shoulders which are adapted to extend beneath an enlarged head 15 at the upper end of pintle 6. When the pintle is pressed into the sleeve, strips 10 and 11 flex outwardly to permit the head 15 to pass shoulders 14, the sleeve then springing back into position. When so mounted, the top surface of the pintle rests in frictional contact with the transverse strip 11' at the top of the sleeve, the pintle being mounted to rotate freely within the sleeve. The pintle is centered within the sleeve by means of the head 15 at the upper end of the pintle, and a curved enlargement 16 which preferably is formed at the lower end of the pintle, journaled within the lower portion of the sleeve which extends through the leg-supporting disk.

The spring frame 6 preferably comprises a transverse portion 17 and a pair of depending spring arms 18, the lower ends of which extend within the upturned flange 2 of the leg mount. When the leg mount or supporting disk is slipped onto the lower end of a tubular leg, the spring arms 18 of frame 5 engage within the leg to frictionally hold the leg mount and attached parts in place. The transverse portion 17 of the spring frame may be riveted or otherwise secured to the top members of the sleeve. I prefer, however, to spot-weld the transverse portion of the spring frame to the top members of the sleeve which may readily be accomplished because of the thickness of metal provided by the two crossed strips 10' and 11'. With this construction it will be noted, the top bearing consists of three layers of sheet-metal secured together, the bearing thus being sufficiently strong and rigid to bear a considerable weight even though the different strips are made of quite thin material.

The leg-supporting disk 1 is provided on its under surface with an arched portion or portions adapted to slidably bear the weight of the furniture when the caster wheel and pintle are not in place. As illustrated, this may comprise a downwardly curved circular ridge 19 surrounding the central opening of disk 1. Disk 1 may be provided with other strengthening corruga-

tions if desired. With this construction, the leg-supporting plates may be positioned upon the lower ends of the legs of an article of furniture, when the latter is to be shipped to a customer for example, the pintles and attached caster wheels being separately shipped. During this time the leg mounts 1 comprise sliding shoes, so that the furniture may readily be moved over carpets or polished surfaces without damage, while at the same time the lower ends of the furniture legs are protected by the leg mounts. It should be noted that with this construction caster wheels and pintles of standard or stock construction may be used, it only being necessary that the pintles of the same be of the proper size.

The construction shown in Figs. 5 and 6 is the same as that described above, except that the leg-supporting disk 1 does not have the peripheral flange 2 surrounding the lower end of the leg, but instead has a plurality, four being illustrated, of upwardly bent projections 2'. These projections may be small ears integral with disk 1 formed by necking the periphery of the disk and bending the ears upward, at points inward from the periphery of the disk, a distance approximately equal to the thickness of the wall of the leg, so that ears 2' slidably engage the inner surfaces of the leg at spaced intervals. The spring frame and the other parts are or may be the same as before, disk 1 being shown with an annular bearing surface 19'. The pintle and caster wheel are not shown in these figures. The ears 2' in Figs. 5 and 6 perform the same functions as does flange 2 in Figs. 1 to 4, namely to limit the outward movement of spring arms 18 when the device is not mounted in a leg, and to center the device with relation to the leg when it is mounted therein. A pair of the ears 2' are located in line with arms 18, the arms extending within and abutting against these ears when the device is not mounted in a leg. Ears 2' fit snugly within the leg, when the spring frame is pressed therein, so that not only is the device held resiliently in the leg, by arms 18, but also positive abutments are provided on the disk, to cause the device to move with the leg in all movements of the latter. The same functions are performed in the case of the outside flange 2 of Figs. 1 to 4, but an outside flange cannot always be used.

A further modified construction is shown in Fig. 7, in which the leg-supporting disk 1' is shown as not having either the upturned peripheral flange 2 or ears 2' previously described. In this case the construction will be the same as before, except that means should be provided to prevent undue compression or outward bending of the lower ends of the spring frame. Accordingly I have illustrated an inverted U-shaped spring

frame, the top horizontal portion 17 of which is secured to the top of the sleeve as before. The arms 18' of the frame, which frictionally engage within the leg, are provided in the form described, with inwardly-bent lower ends 18² and 18³, which have elongated slots 20, 20 therein through which the sleeve 4 extends, these slots being long enough to prevent a certain amount of inward and outward movement to the spring frame. Such provisions are desirable when the flange 2, or ears 2', which otherwise protected the free ends of the spring frame, is omitted.

Having described my invention, what I claim as new therein and desire to secure by Letters Patent of the United States is:

1. In a caster, the combination of a leg-supporting plate having a central opening therethrough and having upturned marginal bearing means adapted to slidably coact with the lower end of a hollow leg, a sleeve secured to said plate about said opening and extending upwardly therefrom, said sleeve being closed at the top to form a top pintle bearing, and a spring frame having a transverse portion secured across the top of said sleeve and having depending arms extending within and abutting against said upturned marginal means when not positioned in a furniture leg, and adapted to frictionally engage the interior of the leg, when mounted therein, substantially as set forth.
2. In a caster, the combination of a leg-supporting plate having a central opening therethrough, and an upturned marginal flange adapted to slidably fit about the lower end of the leg, a sleeve secured to said plate about said opening and extending upwardly therefrom, said sleeve being closed at the top to form a top pintle bearing, a

spring frame having a transverse portion secured across the top of said sleeve, and having depending arms extending within said flange and adapted to frictionally engage within the furniture leg, and a pintle adapted to extend through said opening and sleeve, into contact with the closed top of said sleeve, substantially as set forth.

3. In a caster, the combination of a leg-supporting plate having a central opening therethrough, a sleeve secured to said plate about said opening and extending upwardly therefrom, said sleeve having two portions extending across the top, one superposed upon and contacting the other to form a top pintle bearing, and a spring frame having a portion extending across and secured upon said top sleeve portion, and portions adapted to resiliently engage within a tubular leg, substantially as set forth.

4. In a caster, the combination of a leg-supporting plate having a central opening therethrough, a sleeve secured to said plate about said opening and extending upwardly therefrom, said sleeve being formed of a plurality of spaced strips having transverse top portions, which cross and contact each other, to form a top pintle bearing having a plurality of layers, and a spring frame having a portion extending across and secured upon said top sleeve portion, and having arms at the ends of said secured portion, adapted to frictionally engage within a furniture leg, substantially as set forth.

This specification signed and witnessed this 8th day of March, 1916.

ALBERT B. DISS.
